UNITED STATES PATENT OFFICE.

ERNEST S. JOHNSON, OF WEBSTER CITY, IOWA.

IRONING BOARD.

Application filed March 5, 1923. Serial No. 622,825.

The object of my invention is to provide an ironing board which is simple in construction and which can be easily set up or taken down, and which can be manufactured 5 and marketed at a comparatively low cost.

More particularly, it is my object to provide an ironing board in which the board element is supported by three legs which are capable of movement independently of each 10 other.

Still another object is to provide in such a structure, leg members which will rigidly hold the board member in proper position and which leg members are not in any way 15 connected together by braces or the like.

Still a further object is to provide an ironing board with the leg members thereof so arranged that the floor space between the leg members will be left clear, so that a 20 clothes basket may be placed below the ironing board.

Still a further object is to provide sockets for receiving the upper ends of the leg members and which are so arranged that the leg 25 members, when in operative position, will be held against sideward movement thereby eliminating any sideward or "crawling" movement of the ironing board.

Still another object is to provide a yielding connection between the leg members and the board member for holding the leg members either in their operative or inoperative 30 position when once assumed.

Still a further object is to provide an ironing board which is so arranged that one of the leg members may be moved to closed position so that a dress may be slipped over 35 the entire board for ironing purposes.

Still a further object is to provide a reinforcing beam on the under side of the board member, which is provided with two inclined surfaces to which two of the leg members are secured, thereby causing the leg members to spread outwardly when in their 40 raised or operative position.

Still a further object is to provide an ironing board having legs pivotally secured thereto and so arranged that the legs will become more firmly locked in operative 45 position when more pressure is applied upon the board member.

With these and other objects in view, my invention consists in the construction, arrangement and combination of the various parts of my device, whereby the objects contemplated are attained, as hereinafter

more fully set forth, pointed out in my claims, and illustrated in the accompanying drawings, in which:

Figure 1 is a plan view of the underside 60 of my ironing board, the inoperative position of the leg members being shown in dotted lines.

Figure 2 is a side elevation of the same.

Figure 3 is a detail, sectional view taken 65 on line 3—3 of Figure 2, showing one of the inclined surfaces of the reinforcing beam. Figure 4 is a plan view of the underside of one of the socket members.

Figure 5 is a sectional view taken on line 70 5—5 of Figure 2; and

Figure 6 is an enlarged, sectional view taken on line 6—6 of Figure 1, one position of the leg member being shown in dotted 75 lines.

In the accompanying drawings, I have used the reference numeral 10 to indicate generally an ironing board member which is of the ordinary construction and of the ordinary shape. Secured to the underside of 80 the board member 10, near the rear end thereof, is the reinforcing beam 11. The beam 11 is provided with a pair of inclined faces 12 and 13 near each of its ends. The beam 11 is provided with flanges 14 which 85 abut against the ironing board member 10 and are secured thereto by means of the screws or the like 15.

The reinforcing beam 11 is provided with an enlarged opening between the inclined 90 surfaces 12 and 13 for eliminating part of the weight of the beam. The reinforcing beam 11 will prevent the cracking or warping of the board member 10 and also serves as a means to which two of the leg members 95 may be secured.

A socket 16 forms a part of my leg structure. A socket member 16 is secured to each of the inclined surfaces 12 and 13 of the beam 11. The socket member is provided 100 with a bottom 17 arranged in two parts which are in different planes. The adjacent ends of the two parts of the bottom 17 are connected together by a wall 18.

The upper edge of the socket 16 is provided with an outwardly extending flange 19, which is spot-welded to the beam 11.

A socket 16 is also secured to the underside of the ironing board 10, near the front end thereof and this socket is similar to the 110 socket secured to the surface 12 and 13 upon the beam 11. The socket member, which is

secured near the forward end of the ironing board member 10 is so arranged that when all three of the legs of the ironing board are in operative position the board member will be level.

The bottom of each socket is provided with an opening A. The opening A also extends into the wall 18. The ends of the opening A are tapered, as at 20. Instead of having the ends of the opening meet at a point, I form a notched portion 21, the purpose of which will be hereinafter more fully set forth.

Received within each of the openings A in the sockets 16 are the leg members C. The leg members C are composed of a pair of substantially similar members 22 and 23. The member 22 is formed of a flat piece of metal having a longitudinal reinforcing rib 24 formed midway between its side edges. The purpose of the rib 24 is to reinforce the member 22.

A pair of inclined walls 25 are formed from the member 22 and have outwardly extending flanges 26 on their free edges. The member 23 is constructed similar to the member 22 and is provided with a reinforcing rib 27 and with inclined walls 28.

On the free edges of the inclined walls 28 are the flanges 29. The flanges 29 are designed to rest against the flanges 26 and are somewhat smaller than the flanges 26. The flanges 26 are bent around the flanges 29 for forming a hollow leg member, as clearly shown in Figure 5 of the drawing. The flanges 26 and 29 may be spotwelded together for holding the leg member against twisting or any other undesired movement.

From the construction of the parts just described it will be seen that the members 22 and 23 form a hollow leg member which is made of comparatively light material and yet, with its particular construction and arrangement, is very strong and efficient.

The upper ends of the leg members C are beveled so as to provide a point 30. The leg members project into the openings A in the sockets 16.

A bolt or pivot member 31 is mounted in the walls of the socket 16. The leg members are each provided with an elongated opening 32. The bolt member or pivot 31 extends through the elongated opening 32 in the leg member and prevents the removal of the leg member from the socket.

A coil spring 33 is fixed to the pivot 31 at one end and is received within the hollow leg member C. The free end of the spring 33 is hooked over a pin 34, which has its ends fixed in the sides of the leg member C.

From the construction of the parts just described, it will be seen that the spring member 33 is completely enclosed by the leg member C. The spring 33 tends to pull

the pin member 34 towards the pivot member 31 or in other words, to draw the leg C towards and into the socket member 16.

The connecting of the leg member to the pivot or bolt 31, by means of the spring 33 gives me a loose yielding connection between the socket or board member 10 and the leg members C, which is very desirable.

A flat plate 35 is interposed between the beam 11 and the underside of the board member 10 so that the upper end of the leg members may rest or travel thereover, when moved from one position to another.

A plate 35^a similar to 35 is interposed between the socket 16 near the front end of the board member and the underside of the board member. The plate 35 is provided with a raised portion or projection 36, as clearly shown in Figure 6 of the drawings. The plate 35^a has a projection similar to 36 on the plate 35. One end wall of the socket 16 is also provided with a raised portion 37.

When the leg member is in its inoperative position, it is arranged substantially parallel with the board member 10, as shown in Figure 6.

The point 30 on the upper end of the leg member is received just below the projection or raised portion 37. The spring 33 tends to force the point 30 against the wall of the socket 16.

When the leg member C is swung to operative position, it is necessary to overcome the spring tension and have the point 30 ride over the projection 37. The inclined surfaces 12 and 13 are provided with openings so that the upper end of the legs may project therethrough and ride against the plate 35.

When the leg member is in the position, shown in solid lines in Figure 6 of the drawings, it will be yieldingly held in that position due to the tension of the spring 33. When the leg member C is moved to operative position it is necessary to cause the point 30 thereof to ride over the projection 36.

The inclined wall member 28 of the leg will fit into the tapered ends of the opening A in the socket member 16. The leg members C when in operative position, are inclined from vertical and the greater the pressure upon the board element 10, the tighter the engagement between the leg members and the tapered ends of the opening A.

The notched portions 21 of the opening A are designed to receive the flanges 26 and 29 of the leg member C. The portions 21 in the openings A are larger than the flanges 26 and 29 so that if there is any wear on the inclined sides of the opening A, which forms the tapered ends, the only thing that will happen will be to permit the leg mem-

bers to move a little closer to the ends of the opening without any danger of the flanges of the leg members striking against the edges of the open portions 21.

5 When the leg members are in the position shown in dotted lines in Figure 6, they will be held against accidental closing, due to the tension of the spring 33 and the projection 36.

10 It will be seen that when the leg member is in operative position, it will fit into the tapered ends of the openings A in such a manner that there will be no possibility of any sideward movement of the leg members,

15 thus giving me a very rigid ironing board structure without the use of any connecting braces between the lower ends of the legs.

The lower ends of the leg members may be provided with rubber foot pieces 38, 20 which can be secured to the leg members by any suitable means.

25 The arrangement of the leg members so that there are no cross braces or connections between the lower ends thereof is quite an advantage because it gives me clear floor space below the ironing board for receiving a clothes basket or the like.

The front leg member may be moved to inoperative position and a skirt slipped over 30 the board member for ironing purposes. The front end of the ironing board may then be supported upon a table or a chair. The fact that the leg members are each arranged to operate independently of the others, makes it possible to move one to inoperative position when it is desired to iron a dress or the like.

There being no cross pieces or connecting 40 parts between the lower ends of the legs, permits one of the leg members to be moved to inoperative position without in any way affecting the efficiency of the other two.

The yielding connection between the ironing board and the leg members makes it possible 45 to hold the legs in inoperative position when that position is assumed, or in operative position, when that position, when that position is assumed.

It will be seen that I have provided a very 50 efficient ironing board in which the leg members may be easily and quickly moved to either operative or inoperative position and when once moved to either of their positions, will be yieldingly held in such positions.

55 Some changes may be made in the construction and arrangement of the various parts of my invention, without departing from the real spirit and purpose of my invention and it is my intention to cover by 60 my claims, any modified forms of structure or use of mechanical equivalents, which may be reasonably included within their scope.

I claim as my invention:

1. An ironing board of the class described 65 including a board member, three leg mem-

bers for supporting said board member each being capable of movement independently of the other, two of said leg members being projected outwardly and rearwardly from the board member when in operative position, a 70 pair of socket members mounted upon the underside of the board and at an angle thereto for two of said leg members and a socket for the other leg member secured to the underside of the board member and said 75 sockets having the upper ends of the leg members received therein, said leg members being loosely and pivotally connected to said socket members.

2. An ironing board of the class described 80 including a board member, a reinforcing beam on the underside of the board member, said beam having two inclined surfaces, a socket secured to each of said inclined surfaces and a socket secured to the underside 85 of the board member, a leg member for each of said sockets loosely connected thereto and partially received therein and adapted to engage the socket at two different points for retaining said leg members in operative 90 position.

3. An ironing board of the class described 95 including a board member, a reinforcing beam on the underside of the board member, said beam having two inclined surfaces, a socket secured to each of said inclined surfaces and a socket secured to the underside of the board member, a leg member for each of said sockets loosely connected thereto and partially received therein and adapted to engage the socket at two different points for retaining said leg members in 100 operative position and means for yieldingly holding said leg members either in their operative or inoperative positions.

4. An ironing board of the class described 105 including a board member, a reinforcing beam on the underside of the board member, said beam having two inclined surfaces, a socket secured to each of said inclined surfaces and a socket secured to the underside 110 of the board member, a leg member for each of said sockets pivotally and slidably connected thereto and having one end received in each of said sockets, and means for yieldingly drawing said leg members into said 115 sockets.

5. An ironing board of the class described 120 including a board member, a reinforcing beam on the underside of the board member, said beam having two inclined surfaces, a socket secured to each of said inclined surfaces and a socket secured to the underside of the board member, each of said sockets having an opening in its underside the ends 125 of which are notched, and leg members extended into the openings in said sockets and arranged to be received in the notched ends of said openings when in operative position.

6. An ironing board of the class described 130

including a board member, a reinforcing beam on the underside of the board member, said beam having two inclined surfaces, a socket secured to each of said inclined surfaces and a socket secured to the underside of the board member, each of said sockets having a bottom therein having parts ar-

ranged in two different planes, said bottom parts having an opening therein with notched ends, and leg members extended into the openings in said sockets and arranged to be received in the notched ends of said openings when in operative position.

ERNEST S. JOHNSON.
